COMBINED PIPE RACK, TOBACCO RECEPTACLE, ASH TRAY, AND MATCH BOX

Lee Anderson, Glen Rock, Pa.

Application December 5, 1957, Serial No. 48,785

Term of patent 7 years

(Cl. D85—2)

Fig. 1

Fig. 2

Fig. 3

Fig. 4

Fig. 1 is a top plan view of a combined pipe rack, tobacco receptacle, ash tray and match box, showing my new design;

Fig. 2 is a side elevational view;

Fig. 3 is a sectional view taken on the line 3—3 of Fig. 1; and

Fig. 4 is a rear elevational view thereof.

I claim:

The ornamental design for a combined pipe rack, tobacco receptacle, ash tray, and match box, as shown.
